UNITED STATES PATENT OFFICE.

ABRAHAM P. STEEL, OF STOCKTON, CALIFORNIA, ASSIGNOR OF THREE-FIFTHS TO WILLIAM S. CHRISMAN, HENRY T. OGELVIE, AND CLARK F. JOHNSTON, OF STOCKTON, CALIFORNIA.

NUT-LOCK.

SPECIFICATION forming part of Letters Patent No. 784,014, dated February 28, 1905.

Application filed November 8, 1904. Serial No. 231,865.

To all whom it may concern:

Be it known that I, ABRAHAM P. STEEL, a citizen of the United States, residing at Stockton, in the county of San Joaquin and State of California, have invented certain new and useful Improvements in Nut-Locks; and I do declare the following to be a full, clear, and exact description of the invention, such as will enable others skilled in the art to which it applies to make and use the same, reference being had to the accompanying drawings, and the figures of reference marked thereon, which form a part of this specification.

My invention relates to improvements in nut-locks; and my object is to produce such a device as will effectually lock the nut upon the bolt and also one which will be simple and inexpensive. This object I accomplish by the peculiar construction and adaptation of parts herein fully set forth, and particularly pointed out in the claims appended.

This specification is an exact description of one example of my invention, while the claims define the actual scope thereof.

Reference is to be had to the accompanying drawings, in which similar characters of reference indicate corresponding parts in the several views.

Figure 1 is a side elevation of my improved device, showing the nut locked. Fig. 2 is a longitudinal section of the same. Fig. 3 is a side elevation of my improved nut. Fig. 4 is a vertical section of my improved nut as it appears when locked in position. Fig. 5 is a side elevation of a set-screw. Fig. 6 is a top plan view of a locking-key. Fig. 7 is a horizontal section of a set-screw.

1 designates the bolt, and 2 the threaded portion thereof.

3 is a nut threaded to screw on the bolt as usual. On the inside of said nut is a longitudinal groove 4, in which is inserted a threaded key 5, the threads on said key coinciding with the threads of the nut.

6 is a threaded orifice extending through the side of the nut and opening into the groove 4.

7 designates small ratchets on the outside of the nut 3 encircling the orifice 6.

8 is a set-screw adapted to screw into the orifice 6 and come in contact with the key 5.

On the head of said set-screw is a spring 9, adapted to engage with the ratchets 7. Said spring 9 is secured to said set-screw by means of a tapering head 10, which is driven into a square orifice 11 in the head of said set-screw 8. 55

12 is a threaded orifice extending through the side of the nut 3 opposite the side in which is the orifice 6, and 13 is a set-screw pointed at the lower end and adapted to screw into the orifice 12. 60

The operation is as follows: The nut is screwed up into position, and the set-screw 8 is then screwed up tight, thus jamming the key 5 down onto the threads of the bolt. The springs 9 engaging with the ratchets 7 prevent said set-screw from unscrewing until released from the said ratchets, and thus the nut is absolutely locked and prevented from longitudinal movement on the bolt. To make the nut doubly secured, the set-screw 13 is screwed up tight, thus helping to jam the bolt against the key. This is not absolutely necessary, however, and may be dispensed with, if desired. 70

Not only is my nut secured against outward movement on the bolt, but also against inward movement, thus making it invaluable upon eccentrics and shaftings where a certain amount of play is necessary. 75

Various changes in the form and details of my invention may be resorted to at will without departing from the spirit thereof. Hence I consider myself entitled to all forms of the invention as fairly fall within the scope of my claims. 80

Having thus described my invention, what I claim as new and useful, and desire to secure by Letters Patent, is—

1. The combination in a nut-lock, of a bolt, a nut mounted thereon, a threaded orifice extending through the side of said nut, small ratchets on the outside of said nut and encircling the said orifice, a set-screw seated in said orifice, and a spring secured in said set-screw and adapted to engage with said ratchets, as specified. 90

2. In a nut-lock, the combination with a bolt of a nut mounted thereon, a longitudinal groove in the interior of said nut, a threaded orifice extending through the side of said nut and opening into said groove, ratchets in the side 100

of said nut encircling said orifice, a set-screw seated in said orifice, a spring secured in said set-screw coacting with said ratchets, and a threaded key seated in said groove, as specified.

- 5 3. In a nut-lock the combination with the bolt of a nut mounted thereon, a longitudinal groove in the interior of said nut, a threaded orifice in the side of said nut and opening into
10 said groove, ratchets in the side of the nut encircling said orifice, a set-screw seated in said orifice, a spring secured to said set-screw and

coacting with said ratchets, a threaded key seated in said groove, a threaded orifice in the side of said nut opposite said key, and a set-screw seated in said last-named orifice, as specified. 15

In testimony whereof I have signed my name to this specification in the presence of two subscribing witnesses.

ABRAHAM P. STEEL.
